(57) The ornamental design for a roulette game, as shown and described.

DESCRIPTION

FIG. 1 is a top plan view of my new design for the roulette game; and,

FIG. 2 is a top plan view of a second embodiment of my new design.

The bottom plan, the front, the rear, the left side and the right side views of the roulette game do not form any part of the claimed design.

UNITED STATES PATENT AND TRADEMARK OFFICE
CERTIFICATE OF CORRECTION

PATENT NO. : D738,433 S
APPLICATION NO. : 29/511033
DATED : September 8, 2015
INVENTOR(S) : Cohen

Page 1 of 3

It is certified that error appears in the above-identified patent and that said Letters Patent is hereby corrected as shown below:

The Title page, showing the illustrative figure, should be deleted and substitute therefor the attached Title page.

In the drawings:

Please replace Fig. 2 with Fig. 2 as shown on the attached page.

Signed and Sealed this
Fifth Day of April, 2016
